UNITED STATES PATENT OFFICE.

ELLEN ZIEGLER, OF GREGORY, SOUTH DAKOTA.

BACK-REST.

1,266,374.

Specification of Letters Patent. Patented May 14, 1918.

Application filed March 1, 1916. Serial No. 81,469.

To all whom it may concern:

Be it known that I, Mrs. ELLEN ZIEGLER, a citizen of the United States, residing at Gregory, in the county of Gregory and State 5 of South Dakota, have invented new and useful Improvements in Back-Rests, of which the following is a specification.

This invention aims to provide a back rest, especially designed for use in connection 10 with a bed, whereby the patient or user, may be supported in an upright position without any strain on the body, thereby permitting a relaxation of the muscles and the patient to rest in comfort.

15 In carrying out the invention I provide a device of the above mentioned character, that can be easily and quickly attached to or removed from the bed when desired, and which when in use will adjust itself to the 20 back and comfort of the patient.

Another object of importance resides in the provision of a flexible device of this character, whereby the same can be folded into compact form when not in use.

25 Other objects and advantages, as well as the nature of the invention will be better understood when the following description is read in connection with the accompanying drawing, the invention residing in the construction, combination and arrangement of 30 parts defined in the appended claim.

In the drawing forming part of this specification like numerals of reference indicate similar parts in the several views and where- 35 in:

Figure 1 is a perspective view of the device showing the same in use.

Fig. 2 is a plan view of the device.

The device is primarily intended for use 40 in connection with a bed, herein indicated generally at A. The device consists of a plurality of spaced parallel slats 10 which may be constructed from any suitable material preferably wood, the slats being connected 45 together and held spaced equidistantly by means of the transverse flexible members 11 which are herein shown in the nature of straps. Instead of the straps 11 a webbing of any other suitable material may be em- 50 ployed. However, the straps are adapted to extend beyond the outermost slats and are preferably provided with buckles or the like which are adapted to be adjustably asso- 55 ciated with the extremities of the support- ing members 12. The members 12 consist of two straps which are adapted to be looped

about one of the end rails of the bedstead in the manner clearly shown in Fig. 1, these parts being of any desired length, and by reason of their adjustable connection with 60 the straps 11, the device can be supported at different positions to the comfort of the patient. By reason of the flexible connection between the slats 10, it is manifest that as the supporting members are associated 65 with the straps 12, the slats are arranged in arcuate relation, or in other words adjust themselves to the back of the patient so that the patient or user can rest com- 70 fortably without any undue strain upon the muscles of the body. It will be noted that each of the slats 10 is curved outwardly from a point adjacent the upper ends thereof at a proper inclination to permit a pillow or the like to be inserted between the upper ends of 75 the slats and the back of the user for the purpose of supporting the head.

The device in its entirety can be quickly and easily attached to, or removed from the bed when desired, by reason of the connec- 80 tion between the supporting straps 12 and the adjacent ends of the straps 11. However when the device is in use the upper runs of the straps 12 and straps 11 are inclined to- 85 ward the foot of the bed, and serve in the capacity of arm supports for the patient. When use of the device is not desired, and subsequent to its removal from the bed, the back rest proper may be flattened as clearly indicated in Fig. 2, or it may be rolled or 90 folded in various ways to occupy a minimum amount of space in the room.

It is believed that from the foregoing de- 95 scription the nature and advantages of the invention will be thoroughly understood. However I desire to have it understood that I do not limit myself to the exact construc- 100 tion and arrangement herein delineated and described, and that such changes may be re- 105 sorted to when desired as fall within the scope of what is claimed, and that the vari- ous parts of the device can be constructed from any suitable material without depart- 105 ing from the spirit of the invention.

What is claimed is:

A back rest for bed use comprising a pair of spaced parallel flexible members provided on their ends with buckles, a plurality of 110 spaced slats secured at their ends upon one of said members and secured intermediate

their ends upon the other of said members, the upper ends of said slats being curved outwardly, the device being disposable upon a bed with said slats in a vertical position and 5 said flexible members arranged horizontally, and a pair of vertically disposed straps slidably engaged about a portion of a bed and having their ends engaged by said buckles, pressure of a reclining body against

the curved ends of said slats causing said 10 straps to slide whereby said slats may incline to the same angle as the body.

In testimony whereof I affix my signature in presence of two witnesses.

MRS. ELLEN ZIEGLER.

Witnesses:

FRANK LUNDAK,

Mrs. EDNA NUNAMAKER.
